UNITED STATES PATENT OFFICE.

HARRY L. ASHTON, OF CHICAGO, ILLINOIS.

DESIGN FOR A PICTURE-FRAME.

SPECIFICATION forming part of Design No. 36,690, dated December 22, 1903.

Application filed November 23, 1903. Serial No. 182,424. Term of patent 7 years.

To all whom it may concern:

Be it known that I, HARRY L. ASHTON, a citizen of the United States, residing at the city of Chicago, in the county of Cook and State of Illinois, have invented a new, original, and ornamental Design for Picture-Frames, of which the following is a specification, reference being had to the accompanying drawing, forming part thereof.

The accompanying drawing illustrates a picture-frame embodying my new, original, and ornamental design, such illustration ren-

dering the same clear without further description.

What I claim is—

The ornamental design for a picture-frame substantially as herein shown.

In testimony whereof I have signed my name to this specification in the presence of two subscribing witnesses.

HARRY L. ASHTON.
